UNITED STATES PATENT OFFICE.

EUGENE S. SUTTON, OF SEATTLE, WASHINGTON.

DESIGN FOR A KITCHEN-CABINET.

59,041.

Specification for Design.

Patented Sept. 13, 1921.

Application filed October 25, 1920. Serial No. 419,548. Term of patent 7 years.

To all whom it may concern:

Be it known that I, EUGENE S. SUTTON, a citizen of the United States, residing at Seattle, in the county of King and State of Washington, have invented a new and original and ornamental Design for Kitchen-Cabinets, of which the following is a specification, reference being made to the accompanying drawing, forming part thereof.

The figure is a perspective view of a kitchen cabinet showing my new design.

I claim:

The ornamental design for a kitchen cabinet as shown.

EUGENE S. SUTTON.
